(57) **CLAIM**

The ornamental design for a shower handle as shown and described.

DESCRIPTION

FIG. 1 is a perspective view of a shower handle showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings are for the purpose of illustrating portions of the shower handle that form no part of the claimed design.

1 Claim, 7 Drawing Sheets
